HANDLE FOR CANS OR THE LIKE

Warren E. Galigher, P.O. Box 621, Santa Barbara, Calif.

Filed July 28, 1961, Ser. No. 66,110

Term of patent 3½ years

(Cl. D44—21)

FIG. 1.

FIG. 2.

FIG. 4.

FIG. 3.

FIGURE 1 is a perspective view of a handle for cans or the like and showing my new design;

The portions shown in broken lines are for illustrative purposes only.

I claim:

The ornamental design for a handle for cans or the like, as shown and described.
